Primary Examiner — Richard E Chilcot*(74) Attorney, Agent, or Firm* — Leason Ellis LLP(57) **CLAIM**

The ornamental design for the tire sealing and inflation devices, as shown and described.

DESCRIPTION

FIG. 1.1 is a top perspective view;

FIG. 1.2 is a right side elevation view;

FIG. 1.3 is a left side elevation view

FIG. 1.4 is a front elevation view;

FIG. 1.5 is a rear elevation view;

FIG. 1.6 is a top plan view; and

FIG. 1.7 is a bottom plan view.

The present application relates to tire sealing and inflation devices in which the broken line shown is for the purpose of illustrating portions which forms no part of the claimed design.

1 Claim, 7 Drawing Sheets(56)
